(57) **CLAIM**

The ornamental design for a fishing equipment mount, as shown.

DESCRIPTION

FIG. 1 is a perspective view of the fishing equipment mount of the present invention;

FIG. 2 is front view of the fishing equipment mount of FIG. 1;

FIG. 3 is a back view of the fishing equipment mount of FIG. 1;

FIG. 4 is a left view of the fishing equipment mount of FIG. 1;

FIG. 5 is a right view of the fishing equipment mount of FIG. 1;

FIG. 6 is a top view of the fishing equipment mount of FIG. 1; and,

FIG. 7 is a bottom view of the fishing equipment mount of FIG. 1.

The broken lines show portions of the design that form no part of the claimed design.
